OLIVER J. MERRILL, OF TROPICO, AND JOSEPH G. BLAZEK, OF INGLEWOOD, CALIFORNIA; SAID BLAZEK ASSIGNOR TO SAID MERRILL.

HOLDER FOR BROOMS AND THE LIKE.

1,175,540.

Specification of Letters Patent. Patented Mar. 14, 1916.

Application filed March 20, 1913. Serial No. 755,809.

To all whom it may concern:

Be it known that we, OLIVER J. MERRILL and JOSEPH G. BLAZEK, both citizens of the United States, the former residing at 5 Tropico, in the county of Los Angeles and State of California, and the latter residing at Inglewood, in the county of Los Angeles and State of California, have invented a new and useful Holder for Brooms and the 10 like, of which the following is a specification.

This invention relates to that class of inventions comprising devices to be applied to walls for the purpose of holding either 15 brooms, mops and the like or flexible lines such as ropes or cables.

Objects of the invention are to provide a device of this character which is of very simple and cheap construction and which 20 when mounted upon a wall is adapted to receive and securely hold the handle of a broom or other implement to support the same in a hanging position, and to accomplish this without liability of marring or 25 scratching the handle as it is inserted into or removed from the device.

Heretofore in holders of this character having a pivotal clamping member the action has been dependent upon gravity, it 30 being necessary when introducing a handle to thrust the end thereof upwardly between the supporting and clamping members to first raise the clamping member in opposition to gravity. Accordingly it has also 35 been necessary to mount the holder upon the wall at a height correspondingly greater than the height of the handled implement in order to accommodate the handle end.

In practical use it is found very desirable 40 to mount the holder considerably lower, say at about arm's height, and a specific object of this invention is to secure a lower mounting and to eliminate the aforesaid upward thrust of the handle by so constructing a 45 holder that any portion of a handle may be inserted into direct engagement therewith, thus permitting the introducing by a natural forward movement. With this end in view, when the holder is not in commission, we maintain the clamping arm in a 50 normal open position in opposition to gravity and provide a finger that is adapted to bear against and be operated by the handle to turn the clamping arm upon the introduction of said handle into the holder.

Another object of the invention is to provide a device of this character by which a person may easily, readily and positively support a broom or the like with the action of one hand.

The device when used as a rope holder is particularly useful in securing the ropes of awnings, skylights and the like, and another object gained is the adjustability of the device for different-sized ropes or implement also the ease with which the device may be operated.

The invention is applicable to any form of handled implements being especially serviceable when used as a broom-holder, which 70 application is hereinafter shown and described.

The accompanying drawings illustrate the invention.

Figure 1 is a broken front elevation on a 75 reduced scale of a holder constructed in accordance with this invention, mounted in place upon a wall, and holding a broom. Fig. 2 is an enlarged plan of the holder viewed from line α^2 , Figs. 1, 3 and 4 showing the broom handle held in place. Fig. 3 is an enlarged front elevation of the holder upon a wall, a fragment of which is shown. Dot and dash lines indicate parts of the holder in the normal open position and the 80 broom handle just inserted preparatory to moving said parts into a holding position shown in solid lines. Fig. 4 is a sectional elevation from line α^4 , Figs. 2 and 3. A portion of the broom handle, shown in place 85 in the holder, is broken away to expose parts otherwise hidden. Fig. 5 is a view of the holder analogous to Fig. 3, showing parts in the normal open position preparatory to receiving an implement handle.

Arrows indicate the direction of sight on the various views.

This invention is adapted to be secured to a wall 1 and comprises a base member 2 and a clamp member 3, both of which are preferably made of sheet metal.

The base member 2 may be fastened to the wall by means of counter-sunk screws 4 and terminates at one end in a supporting arm 5 that has an inner concave face 6 against which the handle 7 of the broom 8 or other implement is adapted to be securely held by means of the clamp member 3. Said clamp member 3 is mounted in pivotal relation to the member 2 by means of the 100 105 110

pivot 9 which is preferably a screw extending through holes 10 and 11 in the members 3 and 2 respectively and into the wall 1, said member 3 having at one end a bent portion to form a concavo-convex clamping arm 12 and an extending portion below said bent portion to form an actuating finger 13. The screw 9 is also utilized to hold the clamp member 3 against the base member 2 so that their respective faces press slightly upon each other and this frictional resistance which is thereby produced acts to hold the clamping arm up in opposition to gravity.

The concavo-convex clamping arm 12 is provided with a concave clamping surface 14 conforming to the contour of the broom handle 7 and is substantially triangular in shape, having the lower curved edge 15 cut aslant toward the arm tip, so that said edge tapers upwardly and outwardly to thereby permit free and uninterrupted access for the insertion or withdrawal of the handle as hereinafter described.

The actuating finger 13 constitutes positive means to actuate the clamping arm 12, in opposition to the frictional resistance of the members 2 and 3, to coöperate with the supporting arm 5 and has a tip 16 adapted to bear against and be operated by the broom handle to turn the clamping arm to effect the clamping or releasing of the same handle as hereinafter described.

A stop 17 in the form of a pin mounted in the base member 2 is adapted to be engaged by the upper side of the clamp member 3 forwardly of the pivot 9, as at 18 Fig. 5, to limit the upward movement of said clamp member and its arm 12. Should the member 3 and arm 12 be accidentally knocked from the open position, normally held therein by friction between the two members, the upper side of the member 3 will engage the stop 17 rearwardly of the pivot 9 to arrest said downward movement.

In practical use, when it is desired to support a broom or the like in the holder the handle 7 is inserted between the arms 5 and 12 against the finger tip 16, the clamping arm being frictionally held in the normal open position shown in Fig. 5, and by a slight downward pull of the handle the finger 13 is moved downwardly by its tip to turn the clamping arm 12 of the clamp member 3 about the pivot 9. During this movement of the finger 13 and clamping arm 12 the finger tip 16 carries said handle sidewise to engage with the face 6 of the supporting arm as the clamping surface 14 of said clamping arm is turned into vertical alinement with and bearing against the handle to thereby clamp or wedge the same firmly against said face 6.

When it is desired to remove the broom 65 from the holder a slight upward movement

of the handle will cause the finger tip 16, then contacting with said handle 7, to move the finger to turn the clamp member and its arm 12 upward about the pivot 9 to effect a release of the handle 7, the finger tip meanwhile carrying the handle sidewise from the supporting arm 5 until said clamping member 3 is arrested by the stop 17. The handle is then in position to clear the outer edge 21 of the face 6, and the inside corner of the aslant edge 15 then lies substantially in a transverse plane relative to the plane of movement of the clamping member, shown best by the dot-and-dash position in Fig. 3, so that no interruption is encountered as said handle is withdrawn from the holder. Should, however, the lower edge 15 extend parallel with instead of being inclined to the top edge a resulting lower cornered portion of the clamping arm would necessarily extend in front of the upright handle when the clamping arm was inclined from the vertical which would not only form an obstruction to interfere with the ready insertion or removal at right angles to the holder, but would also graze and scratch the handle as the same was passed therearound. This portion is accordingly cut away leaving the substantially triangular clamping arm having the aslant curved edge 15. In this manner it is made possible to provide the clamping arm with a concave engaging surface that conforms to the side of the broom handle and at the same time avoid any interference to the ready insertion of the handle preparatory to supporting it or to the removal of the handle after releasing it.

It is essential to the effective operation of the holder that the clamping arm 12 engage the implement handle to clamp or wedge the same against the supporting arm somewhat above the horizontal plane of the pivot 9 and to provide adjustment of the holder for different-sized implement handles to thereby maintain practically the same effective wedging angle of the clamp member 3, the latter may be provided with centrally-arranged holes as at 19 and 20 adjacent the pivot hole 10, so that the distance between the arms 5 and 12 may be increased for a larger handle or decreased for a smaller one by utilizing one of the holes 19 or 20, respectively, as a pivotal support.

It is thus seen that a holder is provided comprising a supporting arm and a clamping arm; said clamping arm being provided with a concave clamping surface which constitutes novel clamping or wedging means adapted to coöperate with the supporting arm to securely hold the implement handle as above described. Also said clamping arm is frictionally maintained in a normal open position after the handle is withdrawn, so that any portion of the handle may be again introduced into direct

engagement with the holder by a natural forward and horizontal movement preparatory to clamping, and novel means in the form of a finger is provided to turn the clamping arm, said finger being manipulated by a slight upward or downward movement of the handle after the same is inserted in place between the arms and against the finger.

10 We do not limit the invention to the specific embodiment shown as the device may be used to secure the ropes of awnings, skylights and the like, in which case the holder is mounted upon a wall in an inverted position with the clamping arm adapted to be moved upwardly instead of downwardly to thereby effect a clamping with the supporting arm.

We claim:—

20 1. A holder for the handle of a broom or the like, said holder comprising a stationary arm, a pivotally mounted clamp member frictionally supported relative to said stationary arm, an outwardly bent clamping arm carried by said clamp member and adapted to be turned into and out of clamping relation with the stationary arm, a finger extending from the clamp member and projecting beyond the clamping arm in 25 the produced plane of said clamp member, said finger being adapted to extend rearwardly of the handle and bear against the same when the clamping arm is out of clamping relation to thereby turn the clamping arm into clamping relation when the handle is moved down.

2. A holder for the handle of a broom or the like, said holder comprising a base mem-

ber having a supporting arm provided with an inner concave face, a clamp member 40 pivotally mounted upon and adapted to frictionally bear against said base member, a concavo-convex clamping arm carried by said clamp member, the frictional resistance between said clamp member and said base 45 member being adapted to maintain the clamping arm in a normal open position, and a finger projecting from the clamp member below the clamping arm and adapted to bear against and be operated by the 50 handle to turn said clamping arm in opposition to the frictional resistance between said clamp member and said base member.

3. A holder for the handle of a broom or the like, said holder comprising a base member having a supporting arm provided with an inner concave face, a clamp member pivotally mounted upon and adapted to frictionally bear against said base member, a substantially triangular concavo convex 60 clamping arm carried by said clamp member and provided with a concave clamping surface, said arm having its lower curved edge cut aslant toward the tip, and a finger carried by the clamp member and adapted 65 to bear against and be operated by the handle to turn said clamping arm.

In testimony whereof, we have hereunto set our hands at Los Angeles, California, this 1st day of March, 1913.

OLIVER J. MERRILL.
JOSEPH G. BLAZEK.
